(57) CLAIM

The ornamental design for surface indicia for a package, as shown and described.

DESCRIPTION

FIG. 1 is a perspective view of surface indicia for a package; FIG. 2 is a front elevational view thereof; FIG. 3 is a rear elevational view thereof; FIGS. 4 and 5 are side elevational views thereof; FIG. 6 is a top plan view thereof; and, FIG. 7 is a bottom plan view thereof.

The broken lines are for illustrative purpose only and form no part of the claimed design. The grey scale is not limited to the different shades of grey, but is intended to indicate that the design is not limited to a specific color combination.
